CLAIM

The ornamental design for the chimney cap, as shown and described.

DESCRIPTION

FIG. 1 is a top perspective view of a chimney cap showing my new design;

FIG. 2 is a top plan view thereof;

FIG. 3 is a bottom plan view thereof; and

FIG. 4 is a side elevational view thereof, the other sides being the same as the side shown.

FIG. 1.

FIG. 2.

FIG. 3.

FIG. 4.
